WRISTWATCH

Gordon A. Barlow, Evanston, and Marvin I. Glass, Chicago, Ill., assignors to Marvin Glass & Associates, Chicago, Ill., a partnership

Original design application Mar. 21, 1967, Ser. No. 6,324.
Divided and this application Oct. 13, 1967, Ser. No.
9,150

Term of patent 14 years

(Cl. D42—8)

Fig 1

Fig 4

Fig 5

Fig 2

Fig 3

FIGURE 1 is a top plan view of a wristwatch showing our new design;

FIGURE 2 is an elevational view from the bottom of FIGURE 1;

FIGURE 3 is a bottom plan view of the wristwatch;

FIGURE 4 is an end view of the wristwatch, as seen from the left in FIGURE 2; and

FIGURE 5 is an end view of the wristwatch as seen from the right in FIGURE 2.

This is a division of design application Ser. No. D.6,324, filed Mar. 21, 1967.

We claim:

The ornamental design for a wristwatch, substantially as shown and described.
